BARBECUE BRAZIER

John J. Keal, Los Angeles, Calif., assignor, by mesne assignments, to General Metalcraft, Incorporated, Portland, Oreg., a corporation of Washington

Filed Dec. 7, 1960, Ser. No. 63,146

Term of patent 3½ years

(Cl. D81—10)

FIGURE 1 is a side elevational view of a barbecue brazier showing my new design;

FIGURE 2 is a front elevational view thereof; and

FIGURE 3 is a top plan view thereof.

The element shown near the bottom in FIGURES 1 and 2 is a circular shelf.

My design for a barbecue brazier is characterized by the specifically contoured hood member thereof.

I claim:

The ornamental design for a barbecue brazier, as shown and described.
